UNITED STATES PATENT OFFICE.

GEORGE W. MCKINSTRY AND WILBUR H. SIDDALL, OF ATTLEBORO, MASSACHUSETTS,
ASSIGNORS TO BAY STATE OPTICAL COMPANY, OF ATTLEBORO, MASSACHUSETTS,
A CORPORATION OF MAINE.

CONSTRUCTION OF EYEGLASSES.

Application filed March 1, 1920. Serial No. 362,467.

To all whom it may concern:

Be it known that we, GEORGE W. MCKINSTRY and WILBUR H. SIDDALL, both citizens of the United States, and residents of 5 Attleboro, county of Bristol, and State of Massachusetts, have invented an Improvement in the Construction of Eyeglasses, of which the following is a specification.

This invention relates to the construction 10 of eyeglasses. One of the objects thereof is to provide a device of the above type of simple and durable construction. Another object is to provide a device of the above type adapted to withstand extreme conditions 15 of use without injury. Another object is to provide a device of the above type of attractive appearance adapted to maintain such appearance under hard conditions of use. Another object is to provide a simple 20 and practical art of making an eyeglass which may be quickly and conveniently carried on. Other objects will be in part obvious and in part pointed out hereinafter.

25 The invention accordingly consists in the features of construction, combinations of elements, arrangement of parts, and in the several steps and relation and order of each of the same to one or more of the other 30 steps, all as will be illustratively described, and the scope of the application of which will be indicated in the following claims.

In the accompanying drawings in which 35 is shown one of various possible embodiments of the mechanical features of this invention,

Figure 1 is a rear view of a pair of eyeglasses;

Figure 2 is a sectional view on an enlarged scale taken along the line 2-2 of 40 Figure 1;

Figure 3 is an enlarged detail elevation of an end connection;

Figure 4 is a bottom plan view of the 45 parts shown in Figure 3; and

Figure 5 is an enlarged rear view partially in section illustrating the point of connection with the bridge of the rim.

Similar reference characters refer to similar parts throughout the several views of 50 the drawings.

As conducive to a better understanding of certain features of this invention, it may

be noted that under varying conditions of 55 temperature and moisture, substances analogous to celluloid tend to shrink or expand. In an art of this nature, where appearance is at a premium and security of attachment is valuable in a like degree, this variation in size or shape with a tendency to render 60 the glasses unsightly, or loosen the mounting of the lens, is peculiarly objectionable. To obviate this defect in a simple and practical manner without sacrifice of other 65 advantageous features, is among the dominant aims of this invention.

Referring now to these drawings in detail, there is shown a pair of eyeglasses comprising broadly the bridge 10, lenses 11 and 70 rims 12. Although these eyeglasses are illustrated as of the spectacle form with provision for connection to temple bars, it is to be understood that the term "eyeglasses" is to be used in a broad sense and that many 75 of the features of this invention are applicable to devices of this sort which are held in position by pressure against the nose. It may also be noted at this point that the term "outward" is used to designate a general radial outward direction with 80 respect to the center of the lens; the term "inward" obviously having an opposite significance. Further, the term "end piece" is used in a broad sense, and it may denote 85 one part of a two-piece member or a similar device.

Considering now the construction of these devices more in detail, the bridge 10 is connected directly from the rear with an inner metallic rim member 13. This connection comprises the usual forwardly extending end arm of the bridge shown in cross section at 14 in Figure 5 of the drawings which is permanently jointed at this point to the above metallic rim member. 90 As both sides of the eyeglasses are substantially identical, the construction of one side only will be described.

Rim member 13 extends about the lens 11 in both directions and is preferably of 100 the inwardly concave form shown, adapted to grip the edge of the lens. The ends of this rim member are respectively secured to end pieces 15 and 16, preferably by soldering, the connection being shown in end view 105 in Figure 4 of the drawings. As the con-

struction of these end pieces is substantially identical, that of one only will be described in detail.

End piece 15 as shown in Figures 3 and 4, is provided with an upwardly extending integral sleeve 17 preferably formed by striking up the metal by suitable dies from the body of the end piece. This sleeve lessens in depth, as shown in Figure 3 of the drawings, in an inward direction, and may be cut away on its inner side to permit the edge of the glass at this point to rest directly against the member 13.

In the illustrative embodiment shown, the end pieces are provided with the openings 18 and 19, the former of which receives a screw or other fastening device 20 by which the end pieces are secured together, holding the rim about the lens. The opening 19 is for the pivot 19^a of the swinging temple bar, the latter device not being shown as it forms in itself no part of the present invention.

Recurring now to the general construction of the rim, there is provided an outer rim member 21 formed of "celluloid", the latter term being broadly used to comprehend analogous non-metallic substances. This outer rim member follows about the metallic member 13 substantially in the relation shown in Figure 2 of the drawings. The inner edges 22 of member 21 are, preferably with the latter in a condition softened by heat, swaged or pressed inwardly to interlock with the edges of the metallic member. This interlocking construction, however, although it prevents separation of the parts in a radial direction, is preferably not so tight as to prevent a relative longitudinal movement. Also there is provided preferably an air space 23 between the outer surface of the member 13 and the opposing surface of the member 21, whereby a slight relative inward and outward movement of these parts is permitted. Thus with a tendency of the celluloid to shrink or expand, such movement does no harm. The result, furthermore, is achieved insofar as these features of this invention are concerned, not by the difficult expedient of resisting and preventing the movement, but rather by freely allowing such movement to occur and yet rendering it harmless.

Turning once more to the end construction, the ends of the rim members 21 are fitted within the pockets 17, preferably interlocking throughout their length with the metal member 13. Although certain features of this invention may be achieved if these ends of the member 21 are locked within the sleeves or collars 17, nevertheless it is preferred that these parts have a slip joint connection. In other words, the end of the member 21 as it contracts longitudinally in shrinking, is preferably not held

against such contraction but permitted to move freely in the end of the socket. As the non-metallic rim member 21 shrinks longitudinally the space 23 intervening the member 21 and the metallic rim member 13 permits movement inwardly of the member 21 toward the member 13 to take place, the movement inwardly being substantially in a direction toward the center of the lens. The non-metallic member 21 is thus permitted to contract substantially diametrically and in so doing counteracts or limits the tendency of the longitudinal shrinkage to separate its ends. The socket construction however prevents the opening of any unsightly joint between the end of rim member 21 and the end piece. Thus as rim member 21 shrinks or expands, it is not only permitted to move inwardly and outwardly with respect to the lens, but also preferably may draw endwise, all without weakening the security of mounting of the lens or changing in the slightest degree the appearance of the eyeglasses.

It is believed that the action of the device will be clear from the above, and the art whereby this composite rim member is built up will be briefly set forth as follows. The metallic rim member is formed as shown and the non-metallic or outer member is formed into a rim with its extreme tips somewhat more widely spaced than in Figure 2 of the drawings, otherwise its cross-section being as shown therein. The metallic rim member is then inserted within these end flanges of the celluloid rim, the latter are thereupon preferably heated, and are preferably pressed inwardly at their extreme ends to such an extent as to interlock with the metal member, the parts being so held as to provide the air space 23 during this operation and during the subsequent operation of cooling of the celluloid. It is to be noted that this air space construction permitting relative inward and outward movement even without the interlocking of the edges is of value although there are many advantages in the latter feature.

It will thus be seen that there is provided apparatus and an art in which the several objects of this invention are achieved and in which the advantages hereinbefore referred to are gained.

As various possible embodiments might be made of the mechanical features of the above invention and as the art herein described might be varied in various parts, all without departing from the scope of the invention, it is to be understood that all matter herein set forth or shown in the accompanying drawings is to be interpreted as illustrative and not in a limiting sense.

We claim as our invention:—

1. In eyeglass construction, in combination, an end piece, a non-metallic rim mem-

- ber terminating adjacent thereto, means mounting said rim member and permitting movement of its end relative to said end piece, and means covering the end joint between said rim member and said end piece.
2. In eyeglass construction, in combination, an end piece, a non-metallic rim member, a part connected to said end piece within which the end of said rim member fits and is mounted to slide, and means limiting the extent of said sliding movement of said end of said rim member within said part.
3. In eyeglass construction, in combination, an end piece having formed thereon a socket, a non-metallic rim member having its ends slidably fitted within said socket to slide therein, and means adapted to permit said sliding movement and prevent separation of said rim member and said end piece.
4. In eyeglass construction, in combination, a non-metallic rim member, and a metallic rim member on the inner side thereof and mounted to engage the edge of a lens, said rim members being connected to permit an inward or outward movement of said non-metallic rim member relative to said metallic rim member.
5. In eyeglass construction, in combination, a non-metallic rim member, a metallic rim member on the inner side thereof and mounted to engage the edge of a lens, said rim members being connected to permit an inward or outward movement of said non-metallic rim member relative to said metallic rim member, and means adapted to limit said movement.
6. In eyeglass construction, in combination, a metallic rim member, and a non-metallic rim member positioned outside the same and shaped to interlock therewith at its edges and spaced therefrom in an outward direction.
7. In eyeglass construction, in combination, a metallic rim member, and an outer non-metallic rim member embracing the same having a portion spaced therefrom and a portion interlocked therewith, said members being slidably connected to permit relative endwise movement.
8. In eyeglass construction, in combination, a non-metallic rim member, a metallic rim member on the inner side thereof and mounted to engage the edge of a lens, said rim members being connected to permit an inward or outward movement of said non-metallic rim member relative to said metallic rim member, an end piece to which said metallic rim member is secured, and means forming a pocket in which the end of said non-metallic member is slidably fitted.
9. In eyeglass construction, in combination, a metallic rim member, an outer non-metallic rim member embracing the same,
- said members being slidably connected to permit relative endwise movement, an end piece to which said metallic rim member is connected, and means forming a pocket within which the end of said non-metallic member is slidably fitted.
10. In eyeglass construction, in combination, a metallic rim member, an outer non-metallic rim member embracing the same, and interlocked with its side edges, said members being slidably connected to permit relative endwise movement, and end piece adjacent the end of said non-metallic rim member, and means mounting the end of said non-metallic rim member and permitting movement of its end relative to said end piece.
11. In eyeglass construction, in combination, a non-metallic rim member, a metallic rim member on the inner side thereof and mounted to engage the edge of a lens, said rim members being connected to permit an inward or outward movement of said non-metallic rim member relative to said metallic rim member, and means adapted to limit said movement, said rim members being related to permit relative endwise movement therebetween.
12. In eyeglass construction, in combination, an end piece provided with a pocket, a metallic rim member secured to said end piece, and a non-metallic rim member positioned outside said metallic rim member and embracing the same to interlock therewith, said rim members being related to permit relative movement in an outward or a longitudinal direction and the end of said non-metallic member being slidably fitted within said pocket.
13. The herein described art of forming an eyeglass rim member, which comprises mounting an inner metallic member within an outer non-metallic member, and forcing said non-metallic member into interlocking relation with said metallic member to a degree to prevent separation and permit relative longitudinal movement and relative movement inwardly and outwardly.
14. The herein described art of forming an eyeglass rim member, which comprises mounting an inner metallic member within an outer non-metallic member, with said members relatively spaced in an outward direction, and forcing said non-metallic member into position to interlock with said metallic member and prevent separation thereof while permitting relative movement in an inward and outward direction.
- In testimony whereof, we have signed our names to this specification this 18 day of February, 1920.
- GEORGE W. MCKINSTRY.
WILBUR H. SIDDALL.
